(57) **CLAIM**

The ornamental design of a bearing frame, as shown and described.

DESCRIPTION

FIG. 1 is a top perspective view of a bearing frame showing the present invention;

FIG. 2 is a bottom perspective view of the bearing frame in FIG. 1 showing the present invention;

FIG. 3 is a side view of the bearing frame in FIG. 1 showing one side of the present invention;

FIG. 4 is a side view of the bearing frame in FIG. 1 showing the other side of the present invention;

FIG. 5 is a front view of the bearing frame in FIG. 1 along its longitudinal axis looking into the page showing the present invention;

FIG. 6 is a back view of the bearing frame in FIG. 1 along its longitudinal axis looking out of the page showing the present invention;

FIG. 7 is a bottom view of the bearing frame in FIG. 2 showing the present invention; and,

FIG. 8 is a top view of the bearing frame in FIG. 1 showing the present invention.

The broken line showing of the bearing frame is included for the purpose of illustrating portions of the bearing frame and forms no part of the claimed design.
